Primary Examiner — Mary Ann Calabrese(74) *Attorney, Agent, or Firm* — Mark Terry(57) **CLAIM**

The ornamental design for adhesive label for a container, as shown and described.

DESCRIPTION

FIG. 1 is a front perspective view of an adhesive label for a container, showing the new design;

FIG. 2 is a top perspective view thereof;

FIG. 3 is a top view thereof;

FIG. 4 is a bottom view thereof;

FIG. 5 is a front view thereof;

FIG. 6 is a rear view thereof; and,

FIG. 7 is a side view thereof.

The broken lines shown in the drawings are for illustrative purposes only and form no part of the claimed design.
